UNITED STATES PATENT OFFICE.

ANGUS F. HANNEY AND ALEXANDER GAMMELL, OF CHICAGO, ILLINOIS, ASSIGNORS TO
EUREKA ROUGH DRY PIN SYSTEM CO., OF CHICAGO, ILLINOIS.

TAG HOLDER.

Application filed February 7, 1923. Serial No. 617,539.

To all whom it may concern:

Be it known that we, ANGUS F. HANNEY and ALEXANDER GAMMELL, citizens of the United States, and residents of the city of 5 Chicago, county of Cook, and State of Illinois, respectively, have invented certain new and useful Improvements in Tag Holders, of which the following is a specification.

10 Our invention relates to improvements in tag holders especially designed for holding laundry assorting tags similar in structure to that illustrated in United States Letters Patent No. 1,411,092 issued to Angus F. 15 Hanney and has for its principal object the provision of an improved construction of this character which will be highly efficient in use.

Other objects will appear hereinafter.

20 The invention consists in the combinations and arrangements of parts hereinafter described and claimed.

The invention will be best understood by reference to the accompanying drawings 25 forming a part of this specification, and in which,

Fig. 1, is a side elevational view of a tag holder embodying the invention;

30 Fig. 2, is a top plan view of the same; Fig. 3, is a sectional view taken substantially on line 3—3 of Fig. 1;

Fig. 4, is a sectional view taken substantially on line 4—4 of Fig. 1; and

35 Fig. 5, is a sectional view taken substantially on line 5—5 of Fig. 1.

Referring to the drawings, A indicates the holder which includes a handle 10 carrying a plate 11 having lateral bosses 12 and 40 13 formed on one side thereof. Screw threaded in the boss 12 is a rod member 14 having a tapered extremity 15; the rod member 14 being adapted to receive the laundry tags 16 from the supporting rod 17. The supporting rod 17 is similar in structure to

45 those commonly used in connection with an assorting reel employed by laundries for assorting rough dry work. The rod 17 as shown is channel shaped in cross section and provided with a tapered socket 18 at

50 one end thereof into which the tapered end 15 of rod 14 is adapted to be inserted. The rod 14 when in this position, reference being had to Fig. 1, is adapted to receive the laundry tags from the support 17 by shifting the laundry tags thereonto. Screw

threaded in the boss 13 is a lock rod 19 carrying a catch 20 at its outer extremity, the catch 20 being adapted to clampingly engage the rod 14 adjacent its outer end as shown in Fig. 1. The catch 20 is disengaged from rod 14 upon shifting the laundry tags from the support 17 to the rod and after all the laundry tags belonging to one specific lot are moved onto rod 14 the catch is moved to clampingly engage the rod 60 preventing removal of the laundry tags therefrom. The distance between rod 14 and the lock rod 19 is such that the laundry tags are prevented from pivoting any great distance while carried on the rod 14. 65

As is customary in the system employed by laundries commonly known as wet wash laundries, a number of laundry tags bearing identification numbers are used for sorting out the clothes in lots so that each 70 owner will receive the same number of pieces that he sent to the laundry, the tags of like number being mounted on the support 17 by passing the support through the opening 17 thereof. After these clothes 75 have been removed from the laundry tags our improved tag holder is brought into use and by inserting the tapered end 15 into the tapered socket 18 the laundry tags of like numbers are removed from the support 80 as already herein stated onto the rod 14 and locked on such rod by the catch 20. 85

It is apparent that by the use of our holder we are able to keep the tags of like 90 number together and that the construction of the holder is such that the tags can be conveniently mounted thereon and again removed therefrom when desired. Further it is apparent that our improved tag holder can be economically manufactured and 95 placed upon the market at a small cost.

While we have illustrated and described the preferred form of construction for carrying our invention into effect, this is capable of variation and modification without departing from the spirit of the invention. We, therefore, do not wish to be limited to the precise details of construction set forth but desire to avail ourselves of such modifications and variations as come within 100 the scope of the appended claims. 105

Having described our invention what we claim as new and desire to secure by Letters Patent is:

110 1. A device of the class described includ-

- ing in combination with a laundry tag carrying member, of a supporting member, and an elongated member extending laterally from said supporting member and having means facilitating the positioning of said member in end registration with a tag carrying member whereby the tags can be transferred from the tag carrying member onto the elongated member.
10. 2. A device of the class described including in combination with a laundry tag carrying member having a socket formed in one end thereof, of an elongated member having a tapered end insertable in the socket to facilitate the positioning of said members in end registration, and a handle member carrying said elongated member.
15. 3. A device of the class described including in combination with a laundry tag carrying member, of an elongated member having means facilitating the positioning of said members in end registration with each other, and a handle member carrying said elongated members.
20. 4. A device of the class described including a handle member, an elongated member extending from said handle member adapted to receive articles and having a tapered end portion, an elongated member extending from the handle member and in parallel relation with the first named elongated member and provided with means adapted to engage the first named elongated member adjacent the tapered end thereof for locking the articles on said member.
25. 5. A laundry tag holder including a plate, a handle on said plate, lateral bosses on one side of said plate in spaced relation with respect to each other, a rod member carried by one of said bosses and having a tapered end and adapted to receive a number of laundry tags, and a rod member carried by the other boss, a member on said last named rod member adapted to clampingly engage the other rod member adjacent the outer end thereof to prevent displacement of the tags carried thereon.
30. 6. A device of the class described including a handle member, an elongated member extending from the handle member adapted to receive articles, and means providing a lock to prevent displacement of the articles received by said elongated member.
35. 7. A device of the class described including an elongated member adapted to receive articles, a second elongated member extending in parallel relation with respect to the first named elongated member, and means carried by the second elongated member providing a lock to prevent displacement of the articles received by said first elongated member.
40. 8. A device of the class described including a plate, a handle on the plate, and elongated members carried by the plate in spaced relation with respect to each other, one of said members having a tapered end portion for facilitating the positioning of said member in registration with a tag supporting member whereby the tags carried by said supporting member will be transferred to said elongated member, and means carried by the other of the parallel elongated members providing a lock to prevent displacement of articles received by the elongated member having the tapered end portion.
45. 9. The combination with an elongated supporting member, of an elongated holding member, there being a recess in said supporting member and the end of said holding member being reduced to enter said recess; an elongated stop member arranged adjacent to and substantially parallel with said holding member; and a swinging latch mounted at the end of said stop member and engaging the end of said holding member.
50. 10. A holder of the class described comprising a handle member; an elongated member projecting from said handle member, the free end of said elongated member being provided with means for holding the same in registration with another similar member; a locking member also projecting from said handle substantially parallel with said holding member; and a latch pivotally mounted on the free end of said locking member and engaging said holding member.
55. In testimony whereof we have signed our names to this specification in the presence of two subscribing witnesses.
